(57) **CLAIM**

We claim the ornamental design for a soldering tool, as shown and described.

DESCRIPTION

FIG. 1 is a front perspective view of a soldering tool in accordance with an embodiment of the present invention.

FIG. 2 is a left side view of the soldering tool of FIG. 1.

FIG. 3 is a right side view of the soldering tool of FIG. 1.

FIG. 4 is a front view of the soldering tool of FIG. 1.

FIG. 5 is a rear view of the soldering tool of FIG. 1.

FIG. 6 is a top view of the soldering tool of FIG. 1.

FIG. 7 is a bottom view of the soldering tool of FIG. 1.

FIG. 8 is a front perspective view of the soldering tool of FIG. 1 in an alternate configuration; and,

FIG. 9 is a front perspective view of the soldering tool of FIG. 1 in another alternate configuration.

The portions of the soldering tool shown in broken line form no part of the claimed design.
